UNITED STATES PATENT OFFICE

GUSTAVE G. UTH AND HARRY FEURSTEIN, OF NEW YORK, N. Y.

TIE FASTENER

Application filed July 2, 1928. Serial No. 289,655.

This invention relates to necktie fasteners and has for its object to provide means whereby a necktie can be knotted and held in wearing position without tying it around the collar.

When tying a necktie around a double ply collar difficulty is experienced in adjusting the tie and knot thereof as the part of the tie extending between the two plies is held so tight around the collar that by pulling it one way or the other the tie loses its shape, quickly wears off or even tears.

To obviate this objection I provide a construction that will render it unnecessary to pass the tie around the collar, and permit the tie to be easily and conveniently tied to a knot and to be attached to the front shirt in wearing position, without affecting the appearance of the tie when worn.

Another object of this invention is to provide the device with simple means that will render the attachment and detachment of the tie very easy and that will not be liable to damage the shirt, tear off its buttons or wear out the button holes.

My invention will be more fully understood by reference to the accompanying drawing in which similar reference characters denote corresponding parts and in which Fig. 1 is a front elevation of my tie fastener; Fig. 2 a rear elevation thereof; Fig. 3 a vertical section thereof; Figs. 4 and 5 elevations of the upper part of the fastener of two modified forms of constructions and Figs. 6-8 illustrate the mode of knotting the tie on said fastener.

Referring to the drawing more in detail, 10 denotes a member composed of two longitudinally overlapping sections 10^a, 10^b adapted to be adjustably clamped or otherwise joined together as will be hereinafter described. The section 10^a serves as the tie holder or support proper while the section 10^b, as the means for its attachment to the front shirt.

The section 10^a according to Figs. 1 to 3 is formed at its upper end with a broadened substantially U-shaped or forked head piece 10' in whose vertical legs is fixed a transversely extending rod or wire 11 slightly

curved to conform with the shape of the neck or collar and whose ends are somewhat extended to engage between the two plies of the collar when in position of use. The part below the head piece is reduced in width and slotted longitudinally as at 10² for the purpose to be hereinafter described.

The section 10^b is formed at its upper end with a hook 10³ serving to engage the collar button b. From the lower end thereof projects a resiliently supported finger or member 10⁴ which is adapted to engage the front shirt s, as one of its button holes h (Fig. 3) thereof.

In the present example this finger or member 10⁴ is formed at the end of a rod slidably mounted in a guide member 12 fixed to the rear face of the section 10^b, said rod being actuated by a spring 13 tending to project said member downwardly and outwardly through said guide piece.

These two sections 10^a and 10^b are adapted to be adjustably clamped or joined together so that they can be adjusted longitudinally to lengthen or shorten the device according to requirements. In the present example the clamp consists of a threaded stud 14 on the section 10^b adapted to pass through the slot 10² and receive a clamping nut 15. Suitable means may be provided to prevent the two sections from tilting sideways. According to the present example the section 10^a is formed with upstanding marginal edges 10^c adapted to engage between themselves the section 10^b.

As will be seen from Fig. 3 the head piece of the section 10^a is somewhat bent forwardly or offset from the hooked end 10³ of section 10^b as at 10^e to clear the latter for engagement of the collar button. The same may be convexed on its outer or front face so that the knot may be neatly tied around the same, as will be presently described, without becoming angular.

The loop at the upper end of the head piece, as shown in Fig. 4, may be in form of a safety pin as at 16 or in form of a transversal slot 17 as shown in Fig. 5.

For fastening and knotting it around the section 10^a the tie t is first doubled upon itself

and the folded end t' is passed through the loop of the head piece $10'$ from the rear of the section 10^a to extend down the front face of the latter. Then the two plies t^2 t^3 together are first folded around the front in horizontal manner to form a loop t^4 , as shown in Fig. 6, and then from the rear over the top of said section 10^a through said loop t^4 to extend vertically downward over the part t' , as shown in Fig. 7, thereby producing the knot t^5 shown in Fig. 8.

Instead, after the folded end t' of the tie is passed through the loop of the device in the aforescribed manner, the outer ply of the tie is folded over the top of section 10^a to extend down the front face of the device and then the second ply is folded to form the knot t^5 in the manner heretofore described. The result is the same, except that in the latter case the knot formed is less bulky than in the former.

After the tie is thus neatly tied to a knot, the device 10 is placed in position over the front shirt and fastened by first engaging its hooked end 10^3 with the collar button b and its resilient hooked member 10^4 with one of the button holes h in the shirt s , as shown in Fig. 3. The resilience of the lower hook 10^3 will permit the wearer to bend or move freely without causing the holder 10 to be accidentally detached or tearing or wearing out the button hole.

The device may be cheaply manufactured from sheet metal or other suitable material by stamping and has the advantage of considerably prolonging the life of a tie.

It also has the advantage that once the tie is knotted around it, it need not be untied unless another tie is desired. This will also tend to preserve the neatness of the tie since by repeated tying and untying the tie very quickly becomes stretched and distorted.

The lower part 10^d of section 10^b may be broadened to permit the tie to be clamped thereto by suitable means while worn.

It is of course clear that the device may be greatly simplified and modified in various ways without departing from the spirit of my invention.

I, therefore, do not wish to restrict myself to details described and shown.

I claim—

1. A tie fastener, composed of two longitudinally overlapping sections, adjustably joined together, the upper section being formed with an upper broadened looped part and a lower part of reduced width and the lower section having a hooked part at its top for engagement of the collar button of the wearer and a resiliently supported means for engaging a button or button hole of the front shirt.

2. A tie fastener comprising a loop member on which a tie may be knotted and having a lateral extension of reduced width, a second

member adjustably engaging said extension on said first member, means on the upper end of said second member for the engagement of the collar button of the wearer and means mounted on said second member for engaging on the shirt front.

3. A tie fastener comprising a broadened looped member on which a tie may be knotted and having an extension of reduced width and means cooperating with said extension for the removable attachment of said fastener to the shirt of the wearer, said means including a hook for engaging the collar button and resiliently supported means for engaging the shirt front.

4. A tie fastener as per claim 9 in which the resiliently supported means is in the form of a spring actuated finger whose lower end is capable of engaging a button hole of the shirt.

In testimony whereof we affix our signatures.

GUSTAVE G. UTH.
HARRY FEURSTEIN.
